UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY

HEEL.

No. 880,898.

Specification of Letters Patent. Patented March 3, 1908.

Application filed December 22, 1905. Serial No. 292,933.

To all whom it may concern:

Be it known that I, THOMAS LUND, a citizen of the United States, residing at Beverly, in the county of Essex and Commonwealth of Massachusetts, have invented certain Improvements in Heels, of which the following description, in connection with the accompanying drawings, is a specification, like reference characters on the drawings indicating like parts in the several figures.

This invention relates to heels for boots or shoes.

In the manufacture of boots and shoes, as is well known, heels are commonly attached by machines which act first to press the heel upon the heel seat of the shoe with considerable pressure and then to drive the attaching nails into the heel. It is desirable that the heel be positioned accurately upon its seat in the operation of driving the nails, for while a slight inaccuracy in position may be at times substantially cured in trimming the heel, this cannot always be done, and if the inaccuracy be considerable it may be impossible to trim the heel to secure the symmetry of form desired.

An object of my invention is to provide a heel which will facilitate an accurate location of the heel upon the boot or shoe preliminary to driving the nails. The heel seat of a boot or shoe, as is well known, is the grain side of the leather and immediately prior to the heel attaching operation is commonly quite smooth. There is some liability of a heel slipping upon this smooth surface when pressed upon it and consequently being displaced. Such liability is considerably increased when the heel seat face of the heel is the grain side of the leather and has been subjected to the action of the heel compressor, which, as is well known, in molding heels imparts a high degree of smoothness to their exterior surfaces on account of the extreme pressure which the dies of the machine impose upon the heel.

It has heretofore been generally regarded as impracticable, mainly for reasons such as that above given, to make the heel seat face of the heel the grain side of the leather although there are considerations which render it desirable. For example, where compressed heels are sold as a separate article of manufacture it is of course desired to make their appearance as attractive as possible and

the appearance of the heels is much improved if their exterior faces and particularly their heel seat faces are somewhat finished. The natural smoothness of the grain side of the leather is such that where this side is outside the dies of the heel compressor make it extremely smooth, giving the leather a more attractive appearance than where the flesh side is outside.

My invention consists in molding upon the heel seat face of a heel a series of projections comprising parallel ridges which will impart to said face a degree of roughness that will prevent displacement of the heel in the heel attaching operation. The heel seat lift of the heel is preferably arranged with its grain side outside so that this face of the heel after being acted upon by the heel compressor will be in a highly finished condition.

Other features of the invention will be hereinafter described and defined in the claims.

In the drawings, which illustrate a heel forming one embodiment of the invention,— Figure 1 is a perspective view of the heel; Fig. 2 is a perspective view of a portion of the heel enlarged; and Fig. 3 is a vertical longitudinal section of the heel.

The heel shown is formed of a series of superposed lifts, the heel seat lift or inner lift being arranged with the grain outside and the remaining lifts having their flesh sides uppermost, as indicated in the several figures. The heel is molded in a compressing machine to impart to it the desired form and density. In the molding or compressing operation the heel seat face of the heel is suitably indented or embossed to roughen it so that when pressed upon the heel seat it will not slip from the position desired. The bevel 2 at the breast of the heel is preferably left smooth for the reason that it is unnecessary to roughen this face and the general appearance of the heel is improved if it is left smooth and also because liability is thus prevented of the sole being marred by pressure of such a roughened face upon it in attaching the heel. The purpose of the bevel 2, as is well known, is to prevent the breast edge of the heel marring the sole when the heel is pressed upon the heel seat part of the sole. The projections formed are preferably evenly distributed over that part of the heel on which they lie. In the heel shown, the pro-

2
jections are formed as parallel ridges 3 extending obliquely from side to side of the heel, and parallel ridges 4 intersecting the ridges 3 and arranged at an angle to said ridges. It will be seen that the projections are symmetrically arranged upon the heel seat face of the heel, so that the heel has an attractive appearance. The projections are arranged preferably over approximately the entire area of said face, so that the extent of roughened surface in contact with the heel seat of the shoe will be as great as possible. The series of ridges 3 and 4 upon the heel constitute penetrating projections which, when the heel is pressed upon the heel seat in the operation of the heel attaching machine, will indent or penetrate to a limited extent the heel seat face and thus prevent displacement of the heel. The projections upon the heel seat face of the heel are preferably arranged as shown in Fig. 1 to extend not quite to the extreme edge of said face. This feature is of advantage in that it permits a portion of the stock to be removed in the heel trimming operation with-

out causing the projections to be visible at the sides or curved end of heel.

Having described my invention, what I claim as new and desire to secure by Letters Patent of the United States is:—

1. A heel having upon its inner surface penetrating projections formed and arranged to indent the heel seat of a shoe and comprising parallel ridges extending from side to side of the heel.

2. A heel, having upon its inner surface penetrating projections formed and arranged to indent the heel seat of a shoe and comprising a plurality of sets of parallel ridges, the ridges of one set being arranged at an angle to, and intersecting the ridges of another set.

In testimony whereof I have signed my name to this specification in the presence of two subscribing witnesses.

THOMAS LUND.
